(57) **CLAIM**

The ornamental design for a sink, as shown and described.

DESCRIPTION

FIG. 1 is a top perspective view of a sink of the present disclosure;

FIG. 2 is a bottom perspective view of the sink shown in FIG. 1;

FIG. 3 is a front elevational view of the sink shown in FIG. 1;

FIG. 4 is a rear elevational view of the sink shown in FIG. 1;

FIG. 5 is a left-side elevational view of the sink shown in FIG. 1;

FIG. 6 is a right-side elevational view of the sink shown in FIG. 1;

FIG. 7 is a top plan view of the sink shown in FIG. 1; and, FIG. 8 is a bottom plan view of the sink shown in FIG. 1. The broken lines shown in the drawings are for the purpose of illustrating portions of the sink that form no part of the claimed design.
